TOY HOOP ROLLER

Earl L. Frudeger, 2663 Taft St. 80215, and Donald W. Krengel, 9007 E. Oxford Ave. 80237, both of Denver, Colo.

Filed Feb. 14, 1972, Ser. No. 226,360

Term of patent 14 years

Int. Cl. D21—01

U.S. Cl. D34—5 HP

FIG. 1 is a side elevational view of a toy hoop roller showing our new design;

FIG. 2 is a rear elevational view thereof;

FIG. 3 is a front elevational view thereof;

FIG. 4 is a top plan view thereof;

FIG. 5 is a bottom plan view thereof; and

FIG. 6 is a sectional view thereof taken along line 6—6 of FIG. 1.

We claim:

The ornamental design for a toy hoop roller, as shown.
